APPARATUS WHICH FACILITATES THE
CLEANING OF VENETIAN BLINDS

Edward F. Hausam, Normandy, Mo.

Application November 25, 1949, Serial No. 129,440

1 Claim. (Cl. 160—127)

1

This invention relates to improvements in cleaning apparatus. More particularly this invention relates to improvements in apparatus which facilitates the cleaning of Venetian blinds.

It is therefore an object of the present invention to provide an improved device that can facilitate the cleaning of Venetian blinds.

Venetian blinds are useful and attractive, but they do tend to collect dirt and dust from the air. When covered with dirt or dust the Venetian blinds lose much of their attractiveness; in some instances becoming unsightly and detracting from the over-all appearance of the decorations of a room. Efforts are customarily made by householders to remove the dust or dirt from Venetian blinds; and some of those efforts include placing a cleaning mitten or a cleaning cloth in contact with the tops and bottoms of the various slats of the blinds, and moving that mitten or cloth along the lengths of those slats to wipe off the dirt or dust. The principal defects in this method of cleaning are: first, the mitten or cloth cannot clean the tapes of the Venetian blinds, and Venetian blinds with dirty tapes and clean slats are but little better than Venetian blinds that are dirty throughout; and second, the mitten or cloth will either sweep the dirt and dust from the slats onto the tapes or will actually engage those tapes and directly transfer that dirt and dust to those tapes. The usual results of such cleaning efforts are Venetian blinds with tapes that are dirtier than ever.

Other efforts at cleaning Venetian blinds include separating the slats from the tapes, and separating both the slats and tapes from the actuating mechanism and support; and then washing the slats and tapes until they are free of dirt and dust. The separation of the tapes and slats from each other, and from the actuating mechanism and support, are time-consuming and difficult operations; and the subsequent reassembly of the tapes and slats with each other and with the actuating mechanism and support is even more difficult and time-consuming. As a result, Venetian blinds are seldom cleaned in this manner.

Still other efforts at cleaning Venetian blinds include placing the slats and tapes of the Venetian blinds bodily within large tanks of cleaning solution. However such tanks, and the large quantities of cleaning solution required therefor, necessitate a large investment of money. For these reasons, prior efforts at cleaning Venetian blinds have proven to be objectionable. The present invention obviates these objections by providing a cleaning device which obviates any need of large tanks and large quantities of cleaning solution, obviates any need of disassembling the Venetian blinds, and obviates any possibility of dirt or dust from the slats getting onto the tapes. Such a cleaning device thus assures

2

simple, inexpensive, and effective cleaning of Venetian blinds. It is therefore an object of the present invention to provide an improved cleaning device which permits cleaning of the tapes and slats of Venetian blinds without necessitating disassembly of the Venetian blinds, without necessitating large cleaning tanks, and without permitting dirt or dust from the slats to get onto the tapes.

10 The cleaning device provided by the present invention is enabled to facilitate cleaning of the tapes of Venetian blinds because it has a portion thereof that can underlie those tapes and keep water or cleaning solution from running onto the slats. As a result, the tapes can be thoroughly cleaned without any danger of getting dirty water or cleaning solution on the slats. It is therefore an object of the present invention to provide a cleaning device which has a portion that can underlie the tapes of Venetian blinds and keep dirty water or cleaning solution from running onto the slats.

15 To be capable of underlying the tapes of Venetian blinds, the underlying portions of the cleaning devices must have recesses that can receive the cross tapes of the Venetian blind tapes. However, the spacings between the cross tapes of different Venetian blind tapes vary rather widely and would seem to make necessary a number of different cleaning devices with recesses spaced at different distances. By providing a cleaning device which has a number of wide, properly spaced recesses, the present invention enables one cleaning device to fit the cross tapes of all standard Venetian blind tapes. It is therefore an object of the present invention to provide a cleaning device with a number of wide recesses that are properly spaced to receive the cross tapes of different Venetian blind tapes.

20 25 30 35 40 45 50 The cleaning device provided by the present invention is enabled to keep dust and dirt on the slats from contacting the Venetian blind tapes, because it has portions that extend outwardly beyond and enclose the sides of those tapes. Consequently the cleaning mittens and cleaning cloths cannot sweep dirt and dust from the slats onto the tapes and they cannot directly contact those tapes. As a result, the cleaning of the slats can proceed without any danger of dirtying the slats. It is therefore an object of the present invention to provide a cleaning device with portions that can extend outwardly beyond and enclose a Venetian blind tape.

55 The portions of the cleaning device that enclose the sides of Venetian blind tapes are preferably hinged to those portions of the cleaning device which underlie those tapes. Where this is done, those portions of the cleaning device, which enclose the sides of the Venetian blind tapes during the cleaning of the slats, can be

folded outwardly to further protect the slats against the water or cleaning solution used in cleaning the tapes of the Venetian blinds. It is therefore an object of the present invention to provide a cleaning device with hinged portions that selectively protect the tapes and slats of Venetian blinds.

Other objects and advantages of the present invention should become apparent from an examination of the drawing and accompanying description.

In the drawing and accompanying description several preferred embodiments of the present invention are shown and described but it is to be understood that the drawing and accompanying description are for the purpose of illustration only and do not limit the invention and that the invention will be defined by the appended claim:

In the drawing—

Fig. 1 is a front elevational view of a portion of a Venetian blind and it shows two of the cleaning devices, provided by the invention, assembled with the tapes of that blind.

Fig. 2 is a rear elevational view of one of the cleaning devices of Fig. 1, as that device is assembled with a Venetian blind wherein the cross tapes of the Venetian blind tape are spaced apart three and one eighth (3 1/8) inches.

Fig. 3 is a rear elevational view of the cleaning device shown in Fig. 2, as that device is assembled with a Venetian blind wherein the cross tapes are spaced apart four (4) inches.

Fig. 4 is a front elevational view of a Venetian blind tape with which are assembled the two portions of another form of cleaning device provided by the present invention.

Fig. 5 is a front elevational view of the two portions of another form of cleaning device provided by the present invention.

Fig. 6 is a perspective view of still another form of cleaning device provided by the present invention, and

Fig. 7 is a plan view of one of the cleaning devices shown in Figs. 1-3.

Referring to the drawing in detail, the numeral 10 denotes an elongated plate that is folded to have a J-shaped configuration. The front portion of the folded plate 10 is approximately twice as wide as the rear portion of that plate, and the two portions are spaced apart to form a recess that can accommodate an edge of a Venetian blind tape 24. The recess will preferably confine that edge of that tape rather closely; that plate overlying all of the front and one half of the rear of that type. The rear portion of plate 10 and the rear portion of a plate 12, which is similar to plate 10 and is pivoted to that plate, will abut each other when those plates are rotated toward each other about the pivot 14. Those rear portions can, however, be moved away from each other, as by rotating the folded plates 10 and 12 away from each other around the pivot 14. The rear portions of the plates 10 and 12 will coact to form a protective sheath that is coextensive with the rear of the tape 24 of the Venetian blind; and the front portion of the plate 10 will overlie the front portion of plate 12 as well as the front of the Venetian blind tape 24. The folds of plates 10 and 12 will overlie and protect the edges of the Venetian blind tape 24.

A number of notches 16 of one half (1/2) inch depth are provided in the free edge of the rear portion of the folded plate 10, and a small downwardly depending projection 18 is provided at the upper, outer edge of each such notch. The

notches 16 are of uniform depth but varying width and they are spaced apart at varying distances; as for example, the uppermost notch 16 of plate 10 will preferably be three quarters (3/4) inch wide and will be disposed two and one half (2 1/2) inches above the second notch 16 of plate 10. That second notch will preferably be three eighths (3/8) of an inch wide and will be disposed seven eighths (7/8) of an inch above the third notch; that third notch 16 being five sixteenths (5/16) of an inch wide. The fourth notch 16 will be one half (1/2) of an inch wide and it will preferably be one and nine sixteenths (1 9/16) inches below the third notch and one and nine sixteenths (1 9/16) inches above the fifth notch 16. That fifth notch will be five sixteenths (5/16) of an inch wide and will be three quarters (3/4) of an inch above the sixth notch 16. That sixth notch will be three quarters (3/4) of an inch wide and will be two and three sixteenths (2 3/16) inches above the seventh notch; that seventh notch 16 being five eighths (5/8) of an inch wide. The eighth notch 16 is three eighths (3/8) of an inch below the seventh notch 16, and it will preferably be five sixteenths (5/16) of an inch wide. The free edge of the rear portion of folded plate 12 also has notches; those notches being denoted by the number 20. Downwardly depending projections 22, similar to the projections 18, are provided at the upper, outer edges of each of the notches 20. The notches 20 also are of one half (1/2) inch depth and are of varying width; those notches being spaced apart at varying distances. The uppermost notch 20 of plate 12 will preferably be five sixteenths (5/16) of an inch wide. The free edge of the rear portion of folded plate 12 also has notches; those notches being denoted by the number 20. Downwardly depending projections 22, similar to the projections 18, are provided at the upper, outer edges of each of the notches 20. The notches 20 also are of one half (1/2) inch depth and are of varying width; those notches being spaced apart at varying distances. The uppermost notch 20 of plate 12 will preferably be one half (1/2) of an inch wide and it will be two and fifteen sixteenths (2 15/16) inches above the second notch 20. That second notch will be three quarters (3/4) of an inch wide, and it will be two and one half (2 1/2) inches above the third notch 20; that third notch being three eighths (3/8) of an inch wide. The third notch 20 will be seven eighths (7/8) of an inch above the fourth notch 20; that fourth notch being five sixteenths (5/16) of an inch wide. The fifth notch 20 will be one half (1/2) of an inch wide and it will be one and nine sixteenths (1 9/16) inches below the fourth notch 20. The fifth notch will be one and nine sixteenths (1 9/16) of an inch above the sixth notch 20, and that sixth notch will be five sixteenths (5/16) of an inch wide. The seventh notch 20 will be three quarters (3/4) of an inch wide, and it will be three quarters (3/4) of an inch below the sixth notch 20. The eighth notch 20 will be five eighths (5/8) of an inch wide and will be two and three sixteenths (2 3/16) inches below the seventh notch; and the ninth notch 20 will be five sixteenths (5/16) of an inch wide and will be three eighths (3/8) of an inch below the eighth notch 20.

It has been determined that the cross tapes of most commercially available Venetian blind tapes have one of four (4) uniform spacings. Some of those Venetian blind tapes have the cross tapes spaced three and one eighth (3 1/8) inches apart, others have the cross tapes spaced three and one quarter (3 1/4) inches apart, others have the cross tapes spaced three and three eighths (3 3/8) inches apart, and still other Venetian blind tapes have the cross tapes spaced four inches (4) apart. The spacing referred to is the spacing between the cross tapes at one or the other side of the Venetian blind tape; the spacing between alternate cross tapes at opposite sides of the Venetian blind tape being one half (1/2) of that spacing. When the notches 16 and 20 of the folded plates

10 and 12 are dimensioned and spaced as described, those notches can telescope over and receive the cross tapes of most commercially available Venetian blind tapes. For example, as shown in Fig. 2, the folded plates 10 and 12 can have their notches 16 and 20 interfit with the cross tapes of a Venetian blind tape 24 wherein the cross tapes 26 and 27 at the sides of that tape are spaced apart three and one eighth ($3\frac{1}{8}$) inches. As Fig. 2 shows, the first, second, fourth, sixth and seventh notches 16 of the folded plate 10 will receive cross tapes 26 of the Venetian blind tape 24; and the first, second, third, fifth, seventh and eighth notches 20 of the folded plate 12 will receive cross tapes 27 of the Venetian blind tape 24. The projections 19 and 22 will be disposed inwardly of the inner edges of the cross tapes 26 and 27, and they will prevent accidental separation of the folded plates 10 and 12 from those cross tapes. The inner edges of the notches 16 and 20 may engage and slightly bend the outer edges of the cross tapes 26 and 27, but such bending is not objectionable. As shown in Fig. 3, those same folded plates 10 and 12 can be assembled with a Venetian blind tape 25 wherein the cross tapes 26 and 27 are spaced apart four (4) inches respectively. The first, third, fifth and seventh notches 20 of the folded plate 12 will receive cross tapes 27 of the Venetian blind tape 25. Although not shown in the drawing, the same folded plates 10 and 12 can receive and telescope over the cross tapes of Venetian blind tapes wherein the cross tapes are spaced apart either three and one quarter ($3\frac{1}{4}$) inches or three and three eighths ($3\frac{3}{8}$) inches.

An examination of Figs. 2 and 3 will show that the cross tapes 26 and 27 are not always adjacent the upper edges of the notches 16 and 20 of folded plates 10 and 12. It is because of this fact that those notches have to be as wide as they are, and have to be spaced from each other at those varying distances. The wide notches provided by the present invention facilitate the interfitting of the folded plates 10 and 12 with the cross tapes of the various Venetian blind tapes.

The front portion of the folded plate 12 will be one and one half ($1\frac{1}{2}$) inches wide and the rear portion of that plate will be slightly less than three quarters ($\frac{3}{4}$) of an inch wide. The front portion of the folded plate 10 will be slightly more than one and one half ($1\frac{1}{2}$) inches wide; and the rear portion of that plate will be slightly less than three quarters ($\frac{3}{4}$) of an inch wide. When formed and dimensioned in this manner, the folded plates 10 and 12 can enclose the front, rear, and sides of Venetian blind tapes; most such tapes being one and one half ($1\frac{1}{2}$) inches wide. The front portions of the plates 10 and 12 overlie the front of those tapes, and the rear portion of those plates overlie the rear of those tapes, and the folds of those plates overlie the sides of those tapes.

The folded plates 10 and 12 will preferably be made of a lightweight metal such as aluminum or magnesium or of a stiff, readily cleaned, plastic material such as nylon, Lucite, or Plexiglas. Such folded plates can easily be handled by anyone; and they will not constitute an appreciable load for the cords of the Venetian blinds.

The folded plates 10 and 12 can rotate about the pivot 14 to separate the free edges of the rear portions of those plates. Once those edges have been separated it is an easy matter to insert the free edge of the rear portion of plate 12 between the Venetian blind tape 24 and the slats

28 of the Venetian blind. Thereafter the folded plate 10 can be rotated toward the plate 12; care being taken to insure insertion of the free edge of the rear portion of plate 10 between the Venetian blind tape 24 and the slats 28 of the blind. At such time the cross tapes 26 will fit into the notches 16 of plate 10 and the cross tapes 27 will fit into the notches 20 of plate 12. The projections 18 and 22 will be disposed inwardly of the cross tapes 26 and 27 and will hold those cross tapes within those notches. When the confronting edges of the rear portions of the plates 10 and 12 abut, the front, sides and most of the rear of the tapes 24 will be enclosed and protected. Consequently, a cleaning mitten or cleaning cloth can be used to remove dirt and dust from the slats 28 of the Venetian blind without any danger of getting the Venetian blind tapes 24 dirty. There will be no possibility of the cleaning cloth or cleaning mitten sweeping dirt or dust from the slats 28 onto the tapes 24 since those tapes are almost totally enclosed by the plates 10 and 12, and there will be no likelihood of the cleaning mitten or cleaning cloth directly engaging those tapes. As a result, the Venetian blind tapes 24 will remain clean even though the cleaning mitten and cleaning cloth is used carelessly, as is often the case.

When the slats 28 of the Venetian blind have been cleaned, the two folded plates 10 and 12 will be moved apart, as by rotating one of those plates about the pivot 14. Once the two plates 10 and 12 have been moved apart, those plates can be freed from the tapes 24 of the Venetian blind; the cut-away portion of plate 10 above the first notch 16 facilitating assembly or separation of folded plate 10 and Venetian blind tape 24. The plates 10 and 12 of the cleaning device provided by the present invention will preferably be short enough to fit the shorest Venetian blinds. When so dimensioned, those plates will be shorter than the tapes of many Venetian blinds. However, it is a simple matter to successively set the cleaning devices at different levels on the Venetian blind and successively clean the slats 28 at those various levels. It will be desirable to start at the top of the blind and work down. Where the Venetian blind has two tapes, four cleaning devices will be required; two for the front faces of the tapes, and two for the rear faces of the tapes.

Fig. 4 shows two flat plates 30 and 32 which are provided with notches 34 and 38 that are similar to the notches 16 and 20 of the folded plates 10 and 12. The spacing and dimensioning of the notches 34 and 38 of the plates 30 and 32 will preferably be that of the notches 16 and 20 of the folded plates 10 and 12. The notches 34 of the plate 30 will receive and telescope over the lefthand cross tapes of the Venetian blind tape 35, and the notches 38 of the plate 32 will receive and telescope over the righthand cross tapes of that Venetian blind tape. Projections 36 and 40 are provided at the outer and upper edges of the notches 34 and 38, and those projections are similar to the projections 18 and 22 of the folded plates 10 and 12. The notched edges of the plates 30 and 32 are insertible between the rear of tape 35 of a Venetian blind and the front of the slats, not shown, of that blind. The notched edges of the plates 30 and 32 will abut and will provide full and complete support for the tape 35. The outer portions of the plates 30 and 32 will extend over and overlie parts of the front of the slats of the Venetian blind and

thus keep water and cleaning solution from dripping onto those slats.

To use the plates 30 and 32, it is only necessary to interfit the notches 34 and 38 of those plates with the cross tapes of the Venetian blind tape 35 and then move those plates toward each other until their notched edges abut. Thereafter the action of the projections 36 and 40 will cooperate with the frictional forces between plates 30 and 32 and the tape and slats of the Venetian blind to hold the plates 30 and 32 in position. Once the plates 30 and 32 have been used to clean a part of a tape, those plates can be separated from that part of the tape and assembled with another part of that or another tape. It will usually be desirable to start at the top of each tape and work down. To get at the tapes of the blind which face the window, it may be desirable to lift the blind off of its support and reverse it before replacing it. Another way of accomplishing this would be to place two nails in a joist in the basement and suspend the blind from those nails. It will usually be found that only two plates 30 and 32 are needed to clean all of the tapes of a Venetian blind.

Fig. 5 shows two hinged plates 42 and 44; each of those plates consisting of two portions that are held together by a piano-type hinge. The hinged plate 42 has spaced notches 46, and those notches have projections 48 at the outer, upper edges thereof. The hinged plate 44 has spaced notches 50, and those notches have projections 52 adjacent the outer, upper edges thereof. The spacing of the notches 46 and 50 will be such that the hinged plates 40 and 42 can be used with Venetian blind tapes having different spacings between their cross tapes. The spacing and dimensioning of the notches 46 and 50 of hinged plates 42 and 44 will preferably be that of the notches 16 and 20 of the folded plates 10 and 12. The folding plate 42 has a fastener 56 and the folding plate 44 has a fastener 58, and these fasteners are complementary. As a result, those fasteners can secure together the wide portions of the hinged plates 40 and 44.

To use the plates 42 and 44, it is only necessary to place the notches 46 and 50 of those plates in registry with the cross tapes of a Venetian blind tape and then insert the narrow portions of those plates between the rear of the Venetian blind tape and the front of the slats of the blind. Once that has been done, the tape of the Venetian blind can be washed; the wide portions of the hinged plates 42 and 44 can be rotated so one of those portions overlies the other and so both of those portions overlie the front of the tape. At such time, the narrow portions of plates 42 and 44 will constitute a protective sheath for the rear of the tape, the wide portions of those plates will protect the front of that tape, and the hinges of those plates will protect the sides of that tape. A cleaning mitten or a cleaning cloth can then be passed over the top and bottom surfaces of the slats without any danger of getting the tape dirty.

Fig. 6 shows a plate 58 that has the longitudinally-extending edges 60 thereof folded inwardly toward each other. The confronting edges 60 will be spaced apart a distance such that the edges 60 will abut the outer edges of the cross tapes of the Venetian blind tape while overlying the outer edges of the Venetian blind tape. For example, with a Venetian blind tape that is

one and one half (1½) inches wide, the over-all width of the plate 58 will be slightly more than one and one half (1½) inches wide and the space between the confronting edges 60 will be approximately one and one eighth (1½) inches. The edges 60 will be close enough to the front of the plate 58 to enable the plate to frictionally engage the rear of the Venetian blind tape while the front of the plate engages the front of the tape. The plate 58 will thus be able to hold itself in position on the tape. This plate will enclose the front, the sides, and part of the rear of the tape while the slats are being cleaned with a cleaning mitten or a cleaning cloth.

Whereas several preferred embodiments of the present invention have been shown and described in the drawing and accompanying description, it should be apparent to those skilled in the art that various changes may be made in the form of the invention without affecting the scope thereof.

What I claim is:

A protective device that is usable in the cleaning of a Venetian blind, which has vertical tapes with cross tapes and which has slats supported by said cross tapes, to overlie the front and sides and parts of the rear of one of said vertical tapes of said Venetian blind and thereby protect said one vertical tape from contact with cleaning implements during the said cleaning of said Venetian blind and that comprises an elongated narrow surface that is registerable with but wider than the front of said one vertical tape, rearwardly extending surfaces that are narrower than said elongated narrow surface but are wider than the thickness of said one vertical tape, said rearwardly extending surfaces being contiguous with the side edges of said elongated narrow surface and being registerable with the sides of said one vertical tape, and inwardly extending surfaces that are contiguous with the rear edges of said rearwardly extending surfaces and that are registerable with the rear faces of said sides of said one vertical tape, said inwardly extending surfaces being in confronting relation but being spaced apart a distance greater than two thirds the width of said elongated narrow surface, said inwardly extending surfaces and said rearwardly extending surfaces and said elongated narrow surface constituting a continuous barrier from the rear face at one side of said one vertical tape, past the said one side of said one vertical tape, past the front of said one vertical tape, and past the other side of said one vertical tape to the rear face of said other side of said one vertical tape, said inwardly extending surfaces simultaneously engaging the rear of said one vertical tape and the front edges of said slats to maintain itself in assembled relation with said Venetian blind.

EDWARD F. HAUSAM.
